UNITED STATES PATENT OFFICE.

LOUIS H. SCHNEIDER, OF CHESTNUT HILL, MASSACHUSETTS, ASSIGNOR TO MT. VERNON CO., OF KITTERY, MAINE, A CORPORATION OF MAINE.

HAT-SHIELD.

1,149,471.

Specification of Letters Patent.

Patented Aug. 10, 1915.

Application filed September 25, 1913. Serial No. 791,849.

To all whom it may concern:

Be it known that I, LOUIS H. SCHNEIDER, a citizen of the United States, residing at Chestnut Hill, in the county of Middlesex 5 and State of Massachusetts, have invented new and useful Improvements in Hat-Shields, of which the following is a specification.

This invention relates to improvements in 10 hat shields of the type constructed and arranged intermediate a sweat band and the crown of a hat for the purpose of insulating as it were said sweat band from the body of the hat.

15 Many attempts have been made to accomplish the above mentioned result. These have failed for one reason or another, but principally for the reason that the stitches or other means employed to secure the band 20 and shield to the body of the hat conducted the perspiration by capillary attraction from the sweat band through the body of the hat and to the hat band, thereby ruining said hat.

25 The object of the present invention is to provide a shield preferably constructed of celluloid or like material and of a suitable thickness and stability to permit said shield to be secured to the forward portion of the 30 sweat band of a hat, said shield extending across the front of said hat from one temple portion to the other while at its opposite ends said shield is stitched or secured in any suitable manner to the crown of the 35 hat. Means are also provided along the lower edge of said shield which engage the 40 under inner edge of the rim of a hat to prevent said shield from being shoved upwardly when the hat is being placed upon the head of the wearer. By securing said shield to the hat at points adjacent the temple portion thereof the transmission of perspiration by capillary attraction from said sweat band through said securing means to 45 the crown of said hat will be prevented for at said temple portions the sweat band of the hat seldom if ever comes in contact with the forehead of the wearer.

50 The invention consists in the combination and arrangement of parts whereby the above objects and certain other objects hereinafter appearing may be attained as set forth in the following specification and particularly pointed out in the claims.

55 Referring to the drawings, Figure 1 is a

sectional elevation of a hat embodying my invention looking from the rear toward the front interior portion thereof. Fig. 2 is a longitudinal sectional elevation of the hat illustrated in Fig. 1. Fig. 3 is a detail sectional view of a modified form of shield. Fig. 4 is an elevation of another modified form of shield.

Like numerals refer to like parts throughout the several views of the drawings. 60

In the drawings, 5 is a hat consisting of a crown 6 and a rim 7.

8 is a sweat band constructed in the usual manner and extending entirely around the interior of the crown 6 of said hat and 70 secured thereto preferably by stitches 9 extending from a point 10, which indicates the temple portion at one side of said hat, toward the rear thereof and around to a point 10' upon the opposite side of said hat 75 and indicating the temple portion at that side.

80 A stiffener or shield 11, preferably constructed of celluloid or any non absorbent material, is inserted preferably between the sweat band 8 and the crown 6 of said hat and is secured preferably by stitches 19 or in some other manner or suitable securing means to the bottom of the contiguous portion of said sweat band. Said shield 11 is 85 extended upwardly between said sweat band and the crown of the hat to a point substantially above the portion of said sweat band which contacts with the head of the wearer, thus insulating said band from said crown 90 at the portions mentioned.

95 Means are provided along the lower edge of the shield 11 preferably consisting of a bead 12 to engage the inner under edge of the rim 7 and position said shield vertically thereby preventing the same from being shoved upwardly as the hat is placed upon the head of the wearer, while to still further and more completely secure the shield 11 in place within the crown of the hat said shield 100 is secured preferably by stitches 13 at opposite ends thereof to the crown of said hat, said stitches being located at the temple portions of said hat and at points where, as hereinbefore stated, the sweat band will 105 seldom come in contact with the wearer as a result of which there will be no danger of the perspiration being drawn by capillary attraction.

110 The shield 11, as hereinbefore stated, is

carried to a substantial distance above the bottom of the crown 5 and furthermore above the stitches 13, consequently the distance in a straight line from the stitches 5 13 to the point 20 at the top of said shield, see Fig. 2, will be greater than the distance from said stitches 13, in a horizontal line, to the crown of the hat, as for instance, the point "A". Therefore owing to the rigidity 10 and stiffness of the material from which the shield is constructed it will be impossible for said shield to become displaced by any downward movement thereof. The bead 12 also assists in preventing such a 15 movement of said shield as it stiffens the lower edge thereof.

In Figs. 1 and 2 I have illustrated merely a bead 12 formed along the lower edge of the shield 11 and adapted to engage the rim 20 7, but in Fig. 3 I have illustrated another form of shield in which its lower edge 15 is extended outwardly for a substantial distance in the form of a flange 14 whose outer edge is slightly depressed at 16 in order that 25 any perspiration which gathers thereon may be conducted to said edge and precipitated therefrom. This shield is adapted to be secured to the hat in substantially the same manner as that form illustrated in Fig. 2.

30 In Fig. 4 I have illustrated a shield 11 which is provided with an extension 17 at the central portion thereof, this extension being provided for the purpose of securing said shield directly to the crown of the hat, 35 but at a point 18 substantially above the lower edge 15 and above the upper edge of the sweat band 8², which is illustrated in dotted lines, whereby there will be no possible danger of the perspiration being transmitted thereby to said hat.

40 It will be obvious that by providing the shield or stiffener of celluloid, secured to the band in one way or another, said sweat band will be so supported between the temple portions thereof that no means will be necessary between said temple portions for securing said sweat band to the hat, thus absolutely eliminating all chance of the perspiration from the forehead of the wearer 45 of said hat from being conveyed or conducted to the crown of the hat by capillary attraction.

Having thus described my invention what I claim and desire by Letters Patent to secure is:

50 1. The combination with a hat of a sweat band, and a sheet of celluloid secured to said band across the front portion thereof from one temple portion to the other adapt-

ed to reinforce said band and retain the 60 same in shape, and means for securing said celluloid to said hat at said temple portions only.

2. The combination with a hat of a sweat band, a celluloid shield interposed between 65 said band and the crown of said hat at the front thereof, means adapted to secure said shield and said sweat band together, and means to secure said sweat band to said hat from one end of said shield rearwardly 70 around the back and forward to the opposite end of said shield.

3. The combination with a hat of a sweat band, a celluloid shield interposed between 75 said sweat band and the crown of said hat, said shield extending substantially from one temple portion of said hat to the other, means adapted to secure said sweat band and said shield together, means to secure said shield to said hat at points adjacent 80 said temple portions, and means on said shield adapted to engage the rim of said hat to position said shield vertically relatively thereto.

4. The combination with a hat of a sweat 85 band, a shield interposed between said sweat band and the crown of said hat, said shield extending from one temple portion of said hat to the other, means adapted to secure said shield to said hat at points adjacent 90 said temple portions, and a bead formed on the outer face of said shield integral with and along the lower edge thereof adapted to engage the rim of said hat to position said shield vertically relatively to said hat. 95

5. The combination with a hat of a sweat band, a shield interposed between said sweat band and the crown of said hat, said shield extending from one temple portion of said hat to the other, means adapted to secure 100 said shield to said hat at points adjacent said temple portions, means formed on the outer face of said shield along the lower edge thereof adapted to engage the rim of said hat to position said shield vertically 105 relatively to said hat, a projection at the front of said shield adapted to extend substantially above the upper edge of said sweat band, and means to fasten said projection to the crown of said hat. 110

In testimony whereof I have hereunto set my hand in presence of two subscribing witnesses.

LOUIS H. SCHNEIDER.
